The ornamental design for a wall board attachment lug, as shown and described.

DESCRIPTION

FIG. 1 is a front view of a wall board attachment lug; FIG. 2 is a back view thereof; FIG. 3 is a top plan view thereof; FIG. 4 is a bottom plan view thereof; FIG. 5 is a right side view thereof; FIG. 6 is a left side view thereof; FIG. 7 is a perspective view thereof; and, FIG. 8 is another perspective view of the wall board attachment lug of FIG. 1, shown in a configuration of use. The broken lines in FIG. 8 represent environmental subject matter only and form no part of the claimed design.
